UNITED STATES PATENT OFFICE.

GOTHARD LOWENSTEIN, OF NEW YORK, N. Y.

LENS-MOUNTING.

No. 914,149.

Specification of Letters Patent.

Patented March 2, 1909.

Application filed April 11, 1908. Serial No. 426,463.

To all whom it may concern:

Be it known that I, GOTTHARD LOWENSTEIN, a citizen of the United States, and a resident of the city of New York, borough of Brooklyn, in the county of Kings and State of New York, have invented a new and Improved Lens-Mounting, of which the following is a full, clear, and exact description.

My invention relates to lens mountings, my more particular purpose being to produce a lens so readily detachable from the framework which normally supports it and so readily attachable to the same, that any person can instantly remove the lens from the frame or replace it, the construction, however, being such that when the lens is upon the frame it is perfectly rigid and free from lost motion.

Reference is to be had to the accompanying drawings forming a part of this specification, in which similar characters of reference indicate corresponding parts in all the figures.

Figure 1 is a slightly enlarged front elevation showing a pair of eyeglasses equipped with my improved lens mounting; Fig. 2 is a fragmentary elevation still further enlarged, showing the manner in which the spring latch and its accompanying parts are used for the purpose of holding in position the metallic head always carried by the lens; Fig. 3 is a substantially central fragmentary section upon the line 3—3 of Fig. 2, looking in the direction of the arrows, this view showing how the metallic head carried by the lens is hooked into the eye of the stud and is secured by the spring latch; and Fig. 4 is a view somewhat similar to Fig. 3, but showing the lens and the metallic head carried by it as being placed in position upon the stud.

As the mountings for the lenses are alike, it will suffice to describe but one of them. A stud 5 is mounted upon a spring 6 and is provided with a spring latch 7 secured to the stud by the aid of a bolt 8. A stirrup 7^a partially encircles the latch 7 and forms a limiting stop for preventing excessive movement of the latter, as will be understood from Figs. 3 and 4. A supporting rod 9 carries a guard 10 for supporting the eyeglasses upon the nose of the wearer in the usual manner. A screw 11 secures together the spring 6 and the supporting rod 9. The stud 5 is provided with oppositely extending portions 12 integral with it and each having a general arcuate form. The stud 5 is also provided with a slot 13, and extending across this slot is a bridge 14 integral with the stud 5. The

stud is further provided with lugs 15 extending out flush with the outer surface of the spring latch 7 and secured rigidly against the same by peening or hammering, so as to hold the latch 7 firmly in position by aid of the bolt 8.

The spring latch 7 is provided with a slot 16. A lens is shown at 17 and is provided with a metallic head 18 secured rigidly to it by aid of a screw bolt 19. Intermediate the bridge 14 and the stud 5 the slot 13 has a recess 20, and the head 18 is provided with a lug 21 formed into a hook and adapted to extend into said recess 20. The slot 13 of the stud 5 is also so shaped as to form an undercut 22, as will be understood from Fig. 4. The head 18 is provided with a spur 23 which is adapted to slip into the undercut 22 so as to hold the head rigidly in position. The head is provided with a hook 24 which is adapted to pass into the slot 16 of the spring latch 7. The outer or free end 25 of this spring latch is curved slightly, as indicated in Fig. 4.

My invention is used as follows: The operator (who may be any person using eyeglasses) ordinarily wears the glasses without doing anything to them. If, however, he desires, for any reason, to remove the lens, he grasps it between his fingers and at the same time places his thumb nail against the inside of the spring latch 7 at the end 25 of the same. By applying a gentle pressure against this end 25 he bends the spring latch slightly away from the stud 5 so that the slot 16 clears the hook 24. This releases the head 18 and the lens can now be removed by turning it outwardly at the bottom into the position indicated in Fig. 4, the hook 21 simply being next lowered. This all takes place at one operation and so easily that it can be done without the necessity for any special knowledge or training for the purpose.

In order to replace the lens the hook 21 is slipped into the recess 20 so as to engage the bridge 14, and the lens 17 is next forced down so that its central plane coincides substantially with the central plane of the stud 5. The spring latch 7 now clasps into place, the slot 16 encircling the hook 24 and the spur 23 extending into the undercut 22, thereby forming a firm anchorage.

I am aware that the broad idea of a detachable lens is not new, but my particular construction affords special advantages not heretofore attained.

22
I do not limit myself to the particular size or shape shown for any of the parts above described, as reasonable changes can be made without departing from the spirit of my invention.

Having thus described my invention, I claim as new and desire to secure by Letters Patent:

1. The combination of a frame to be worn upon the face, a stud mounted upon said frame and provided with a slot, a lens, a head mounted upon said lens and provided with a portion for entering said slot, and a spring latch for temporarily connecting said stud and said head together.

2. The combination of a frame to be worn upon the face, a stud mounted upon said frame and provided with a slot extending entirely through said stud, the stud being further provided with a bridge bounding a portion of said slot, a lens, a head secured to said lens and provided with a hook for engaging said bridge, said head being further provided with a second hook, and a spring latch for temporarily securing together said last-mentioned hook and said stud.

3. A device of the character described, comprising a frame to be worn upon the face, a stud mounted upon said frame and provided with a bridge, said stud being further provided with an undercut portion, a spring latch mounted upon said stud and extending past said undercut portion, said spring latch

being provided with an opening, and a head provided with a portion for engaging said bridge, and further provided with a spur for extending into said undercut, said head being also provided with a hook for extending through said opening in said spring latch, and a lens connected with said head.

4. The combination of a frame to be worn upon the face, a stud mounted upon said frame, a lens to be supported by said stud, a metallic member secured to said lens and provided with portions extending a little distance along the edges thereof for the purpose of holding said lens, a spring latch, and means controllable by said spring latch for temporarily connecting said metallic member with said stud.

5. The combination with a frame to be worn upon the face, of a stud mounted upon said frame, a lens to be supported by said stud, a metallic member secured to said lens and movable relatively to said stud, a latch for connecting said metallic member and said stud together, and a limiting stop for preventing excessive movement of said latch.

In testimony whereof I have signed my name to this specification in the presence of two subscribing witnesses.

GOTHARD LOWENSTEIN.
